DESIGN FOR A MAGNIFYING GLASS

John R. Miles, West Englewood, N. J., assignor to
Bendix Aviation Corporation, South Bend, Ind.,
a corporation of Delaware

Application February 17, 1945, Serial No. 118,014

Term of patent 14 years

(Cl. D57—1)

To all whom it may concern:

Be it known that I, John R. Miles, a citizen of the United States, residing at West Englewood, county of Bergen, State of New Jersey, have invented a new, original, and ornamental Design for a Magnifying Glass, of which the following is a specification, reference being had to the accompanying drawing forming part thereof, in which:

Figure 1 is a front perspective view of the magnifying glass in a closed position;

Figure 2 is a side elevational view of the magnifying glass in a closed position showing my new design;

Figure 3 is a front perspective view of the magnifying glass in an open position; and

Figure 4 is a side elevational view of the magnifying glass in an open or usable position.

I claim:

The ornamental design for a magnifying glass, as shown.

JOHN R. MILES.
